UNITED STATES PATENT OFFICE.

JOHN J. ALVORD AND FRANK KARSITZ, OF BRIDGEPORT, CONNECTICUT.

DESIGN FOR A SMOKER-STAND.

41,537.

Specification for Design.

Patented July 4, 1911.

Application filed April 11, 1911. Serial No. 620,520. Term of patent 7 years.

To all whom it may concern:

Be it known that we, JOHN J. ALVORD and FRANK KARSITZ, citizens of the United States, residing at Bridgeport, in the county of Fairfield and State of Connecticut, have invented a new, original, and ornamental Design for a Smoker-Stand, of which the following is a specification, reference being had to the accompanying drawings, forming a part thereof.

In the drawings Figure 1 is a front perspective view of a smoker stand, showing our new design, and Fig. 2, shows a top plan view of the same.

We claim:

The ornamental design for a smoker stand, as shown.

JOHN J. ALVORD.
FRANK KARSITZ.
